ABSTRACT: Described is a portable machining apparatus especially suitable for conditioning coke oven door jambs. The apparatus of the invention is adapted to fit in the frame of a coke oven door in place of the door in a position closely adjacent to the door jambs. The apparatus includes an elongated housing having a motor with a cutter connected therewith disposed for longitudinal movement along the housing. The cutter projects an adjustable distance outwardly of the housing so that the cutter is in peripheral engagement with the coke oven door jambs. The motor and cutter are moved longitudinally of the housing by means of screw shafts which are threadingly engaged by the motor case. In normal operation, the motor rotates the cutter as the motor-cutter unit moves longitudinally of the housing so that both door jambs are conditioned simultaneously.

APPARATUS FOR MACHINING COKE OVEN DOOR JAMBS

The present invention relates to metal working equipment and more particularly to apparatus for machining coke oven metal door jambs.

BACKGROUND OF THE INVENTION

coke oven door jambs are usually made of cast iron and are bolted in the coke oven door opening in a fixed position. During the operating life of a coke oven, the door jambs become warped and a deposit of carbonaceous material builds up on the seats or faces of the door jambs. When this condition occurs, the coke oven door cannot be properly seated in sealing relation with the door jambs. With the door imperfectly seated, gases escape from the coke oven during coking operations and cause objectionable smoke and fumes to be emitted into the atmosphere.

Prior to my invention when the coke oven door jambs so deteriorated that gastight seating of the coke oven door therewithin was impossible, the door jambs were replaced with new ones. This, of course, resulted in excessive down time for the coke oven and increased operating costs.

It is, accordingly, the primary object of my invention to provide a portable metal-working apparatus which is eminently suitable for use in machining and reconditioning coke oven door jambs in situ and thus eliminate the need for discarding and replacing warped and "caked" coke oven door jambs and greatly reduce coke oven operation interruptions.

It is more specific object of my invention to provide an apparatus of the character set forth by the above statement of object which consists of an elongated housing having one substantially open side, which housing is adapted to be positioned with its open side closely adjacent a coke oven door frame when the door has been removed therefrom; a motor case disposed for sliding movement longitudinally in the housing; screw shaft means for driving the motor case along the housing; a motor mounted in the case and having a rotary cutter connected therewith and driven thereby, the cutter being adapted to engage with its periphery the spaced jambs of the door frame adjacent which the housing is positioned.

These and other objects will become more apparent after referring to the following specifications and attached drawing in which:

BRIEF DESCRIPTION OF THE DRAWING

FIG. 1 is a front elevational view of the apparatus of the invention;

FIG. 2 is a side elevational view of FIG. 1;

FIG. 3 is a rear elevational view of FIG. 1;

FIG. 4 is an enlarged cross-sectional view of the housing of the invention taken through the cutter unit element;

FIG. 5 is a plan view of the motor shroud of the apparatus of the invention;

FIG. 6 is a substantially diagrammatic cross-sectional view showing the apparatus of the invention mounted in a coke oven door frame in machining position;

FIG. 7 is a perspective view of the motor case of the apparatus of the invention;

FIG. 8 is a partial sectional view taken substantially along the line VIII-VIII of FIG. 2 with parts broken away for clarity of the motor case of the invention showing its engagement with the driving screw shaft elements; and

FIG. 9 is a perspective view of the motor case of the invention showing the disposition of air nozzles for cleaning purposes.

DESCRIPTION OF THE PREFERRED EMBODIMENT

Referring more particularly to the drawing, reference numeral 2 designates generally the elongated housing of the invention which has a substantially open front face 4, solid sides 6 and a perforate rear side 8. A pair of notches 10 is formed on the rear side 8 whereby the housing can be manipulated by the door hooks of a conventional door-extracting machine. The

ends of the housing 2 are covered by plates 12. The end plates 12, which are solid members with openings therethrough for hoses, piping, etc., space the side frame 6 apart and are bolted in place to the sides 6 and the rear sides 8 to make the housing a rigid box. Along the front face 4 of the housing 2, the sides 6 are notched to provide a recess 14 which extends along the lengths of both sides 6.

A motor case 16 which is in the shape of a cup having a substantially closed end 18 and an open end 20 surround by a rectangular flange 22, as best shown in FIG. 7, is snugly but slidably fitted in the housing 2 with its open end 20 facing outwardly of the open face 4 of the housing. Opposite sides 24 of the flange 22 are fitted in the recesses 14 and are retained therein by means of gib 26 which are bolted to the side walls 6. A two-piece cylindrical shroud 28 is slidably fitted within the motor case 16 and restrained from rotational movement therein by means of a key 30. An hydraulically powered motor 32 is disposed within the shroud 28 with its shaft 34 projecting therefrom out of the open face 4 of the housing 2. A collar 36 is keyed to the shaft 34 by means of a key 38, and a cutter blade 40 having "throw away" type carbide inserts 42 spaced around the periphery thereof is attached to the collar 36 by means of bolts 44. The motor 32 is fixedly secured within the shroud 28 by means of bolts 46.

The motor and shroud are adjustable as a unit inwardly and outwardly of the motor case 16 and open face 4 of the housing 2 by means of screw 48. The head 50 of the screw 48 is disposed in a pocket 52 formed in a retaining collar 53 which in turn is disposed between the motor and the side of the shroud remote from the cutter blade 40. The retaining collar is held in position by means of two of the bolts 46. The body or shaft 54 of the screw 48 is threaded through an internally threaded sleeve 56 which is disposed in the bottom wall 18 of the motor case 16. Nuts 58 and 60 lock the shroud motor unit in position. A set screw 62 locks the nut 58 to the sleeve 56. Nut 60 serves as a lock nut to hold the sleeve 56 and nut 58 in place. This arrangement also holds the shroud 28 and the motor 32 to the motor case 16.

The movement of the cutting head unit, made up of the motor case 16, shroud 28, and cutter blade 40, from one end to the other of the housing shaft 2 is accomplished by means of a pair of screw shafts 64 and 64a. The power for rotating the screw shafts 64 and 64a is supplied by an hydraulic motor 66.

The motor 66 is mounted on one of the end plates 12 with its shaft projecting therethrough to a connection with the screw shaft 64. The other screw shaft 64a is driven by a chain and sprocket 96 68 with a drive sprocket 70 on screw shaft 64. It will be noted that, if desired, the rotation of screw shaft 64 could be transferred to screw shaft 64a by means of a gear train coupling, or separate motors could be provided for driving each of the screw shafts independently. The ends of the shafts 64 and 64a remote from the motor 66 are journaled in bearings 72 mounted in the end plate 12 opposite the motor 66. Driving action of the screw shafts 64 and 64a is transferred to the motor case 16 by means of two internally threaded nuts 74 which are welded or otherwise fixedly attached in tangential fashion on the motor case 16, as best shown in FIG. 8. It will be understood that motor case 16 can be case with the nut 74 forming an integral part thereof, if desired. As best shown in FIGS. 4 and 5, the screw shafts 64 and 64a pass through elongated slots 76 in the top and bottom of the shroud 28 so that the screw shafts will not interfere with the adjusting movement of the shroud and motor unit relative to the motor case 16.

A pair of latches, designated generally by reference numeral 78, is provided on each of the side wall 6 of the housing 2 for securing the housing in position when it is moved into a coke oven door frame. Each of the latches 78 includes a pneumatic cylinder 80, a bolt 82, which is attached to the piston rod of the cylinder 80, and a guide 84 which guides the movement of the bolt 82. When the housing 2 is placed within a coke oven door frame, as shown in FIG. 6, the cylinders 80 are actuated to project the bolts 82 through the guides 84 into a catch 85 affixed to the inner part of the door frame.

Positioning stubs 86 project from each of the four corners of the open face 4 of the housing 2. The positioning stubs 86 insure the provision of sufficient space between the inside of the door frame and the housing 2 for the cutter blade 40 to rotate.

If desired, air manifolds 88 and 90 may be provided on the outer surfaces of the motor case 16. Each of the air manifolds is provided with a plurality of air nozzle openings for directing air under pressure to blow chips away from the screw shafts 64 and 64a and the cutter blade 40.

Hydraulic fluid under pressure may be supplied to the motor 32 by means of a conventional fluid conduit connected with a suitable pump and circulating apparatus (not shown). The motor 66 which rotates shafts 64 and 64a likewise be cone connected to a conventional pump and hydraulic control system (not shown).

In operation, when it becomes necessary or desirable to machine the door jambs 94 of a coke oven door frame, a hear heat shield 96 is placed inwardly of the door frame of the coke oven after the door has been removed therefrom so as to seal off the heat from the coke oven during the subsequent machine operation. Then the conventional coke oven door-extracting machine (not shown) is used to pickup the housing 2 from a rack (not shown) on which it normally rests between machining operations and carry it to and place it in operating position in the coke oven door frame with the open face 4 of the frame and the cutter blade 40 facing inwardly of the coke oven with the carbide inserts 42 on the periphery of the cutter blade in engagement with the door jambs 94, as best shown in FIG. 6.

The cylinders 80 are then actuated to project the bolts 82 to lock the apparatus in operating position. The depth of cut desired, depending on the amount of bow in the door jambs, is set by loosening lock nut 60 and rotating the screw 48 to move the shroud and motor unit inwardly or outwardly of the motor case 16. Motors 32 and 66 are then actuated to rotate the cutter blade 40 and turn the screw shafts 64 and 64a, respectively, so as to cause the cutter blade to rotate and the cutter unit to travel longitudinally of the door jambs 94.

I claim:

1. Apparatus for machining the jambs of coke oven door

frames comprising an elongated housing having one substantially open side extending longitudinally therealong, said housing adapted to be positioned with its open side closely adjacent a coke oven door frame when the door has been removed therefrom, a motor case snugly fitting in the housing for sliding movement longitudinally thereof, means for driving the case along the housing, a motor mounted in said case, and a rotary cutter connected with and driven by said motor, said cutter projecting outwardly of the open side of said housing and being adapted to engage with its periphery the spaced jambs of the door frame adjacent with said housing is positioned.

10 2. Apparatus as defined by claim 1 in which said case-driving means include a screw shaft journaled in and extending longitudinally of said housing, motor means connected with said shaft for rotating the same, said case being threadingly engaged on said shaft.

15 3. Apparatus as defined by claim 1 including a shroud surrounding the motor in said case, means securing said motor to said shroud, and means connected with said casing and said shroud for adjustably moving said shroud and motor inwardly and outwardly of said housing normal to the longitudinal axis thereof.

20 4. Apparatus as defined by claim 3 in which said means for adjustably moving said shroud and motor includes a screw having its head disposed for rotation in said shroud, an internally threaded sleeve rigid in said motor case threadingly surrounding the body of said screw, said shroud being adjustably movable inwardly and outwardly of said motor case upon rotation of said screw, and a lock nut threaded on said screw adjacent said sleeve whereby said screw is locked when said shroud is in adjusted position.

25 5. Apparatus as defined by claim 1 including latching means on opposite lateral surfaces of said housing adapted to engage said door frame when said housing is positioned closely adjacent thereto.

30 6. Apparatus as defined by claim 1 including spacer members projecting from said housing adjacent the open side thereof adapted to engage said door frame to thereby limit the distance of penetration thereinto by said housing.
